UNITED STATES PATENT OFFICE.

MILTON ROY SHEEN, OF PHILADELPHIA, PENNSYLVANIA, ASSIGNOR TO TUNNEL MACHINE MANUFACTURING AND ENGINEERING COMPANY, OF PHILADELPHIA, PENNSYLVANIA, A CORPORATION OF DELAWARE.

MACHINE FOR BUILDING TUNNELS AND THE LIKE.

Application filed November 20, 1920. Serial No. 425,534.

To all whom it may concern:

Be it known that I, MILTON ROY SHEEN, a citizen of the United States, residing at Philadelphia, in the county of Philadelphia and State of Pennsylvania, have invented a certain new and useful Improvement in a Machine for Building Tunnels and the like, of which the following is a specification.

My invention relates to improvements in a machine for building sewers, tunnels and the like. My invention also relates to further improvements in a machine for building sewers for which Letters Patent of the United States, No. 1,351,137, were issued to me on the 31st day of August, 1920.

The present invention comprises a machine having a casing, within which a structure is formed of bricks, or building blocks. The machine also includes a rotary cam mounted within the casing for forcing the blocks into place in the structure and for forcing the casing forward through the excavation made by a cutting head.

The object of the present invention is to provide a novel form of rotary cam and bearings for mounting the cam within the casing and also the means for driving the cam; a further object of my invention is to provide a novel form of anti-friction carriages for relieving the friction between the face of the structure and the cam; and a still further object is to provide a bearing ring having rollers thereon between the cam and the bearing secured to the casing. These together with various novel features of construction and arrangement of the parts, which will be more fully hereinafter described and claimed, constitute my invention.

Referring to the accompanying drawings, Fig. 1 is a vertical longitudinal sectional view of my improved machine; Fig. 2 is a transverse section of one-half of the machine, as on line 2—2, Fig. 1; Fig. 3 is a transverse vertical section on line 3—3, Fig. 1, showing a portion of the cam and the bearing ring; Fig. 4 is a transverse section on line 4—4, Fig. 1, showing a portion of the face of the cam; Fig. 5 is a partial vertical longitudinal section on line 5—5, Fig. 2, drawn on a larger scale; Fig. 6 is a perspective view of a portion of the bearing ring; Fig. 7 is a plan view of the carriages,

as shown in the upper portion of Fig. 1, shown detached from the cam and drawn on a larger scale; Fig. 8 is a side elevation of Fig. 7; Fig. 9 is a central section, as on line 9—9, Fig. 8, and Fig. 10 is a transverse section on line 10—10, Fig. 9.

In the accompanying drawings, in which like reference characters refer to like parts, 1 represents the cylindrical casing having at the forward end a cutting head 2 carried by a central shaft 3, mounted in the bearing 4 secured to the casing. The cutting head 2 is rotated by braces 5, secured to a ring-gear 6, rotatably mounted in the bearing collar 8, which is secured to the casing. The ring-gear 6 is rotated by a pinion 7 driven by a motor 9 mounted upon the bearing 4.

The excavation is made through the ground, the proper diameter for the passage of the casing by the cutter head 2.

The sewer or tunnel structure is formed at the rear end of the casing 1 and consists of blocks or bricks 12 which are laid successively by hand, or automatically, to form a cylindrical structure.

A cam cylinder 15, having a spiral cam face 16 is provided within the casing which cam face 16 presses against the anti-friction carriages 18 which in turn press against the blocks 12 and forces them into place in the structure 13 as the cam cylinder 15 rotates. The cam, thus pressing against the carriages, which are positioned against the forward face of the structure, forces the casing 1 forward as the structure is formed by the successive laying of the blocks 12 in the cylindrical structure, which latter is also formed with a spiral forward face corresponding to the spiral face 16 of the cam cylinder 15.

A bearing flange 20 is rigidly secured in the casing and is provided with a cylindrical surface forming a track 21 and also an annular face forming a thrust bearing surface 22. The cam cylinder 15 revolves within the casing upon the concentric track 21 and it is held against longitudinal movement in relation to the casing by the said annular bearing surface 22 of the bearing flange 20, and by the detachable flange plate 23. The latter is secured to the forward edge of the cam cylinder 15 and overlaps the front face of the bearing flange 20.

- A bearing ring 25, having loosely mounted rollers 26 and 27 thereon, is interposed between the bearing faces 21 and 22 of the bearing flange 20 and the cam cylinder 15
- 5 to reduce the friction between the latter and the bearing flange 20. The rollers 27 are mounted upon shafts 28 secured in the bearing ring 25, which shafts 28 are positioned radially on lines extending from the center
- 10 of the bearing ring. The rollers 26 are mounted upon shafts 29 secured in the bearing ring 25, which extend parallel with the axis of rotation of the bearing ring, as shown in Figs. 3 and 6.
- 15 The cam cylinder 15 is provided with a cylindrical bearing surface 30 which rotates upon the rollers 26 of the bearing ring 25 and said cam cylinder 15 is also provided with an annular rib 32 having a facing
- 20 surface 33 which bears upon the rollers 27 of the bearing ring 25.

The bearing flange 20 is provided with an annular groove into which fits a circular dust ring 35 mounted upon the cam cylinder 15, (more clearly shown in Fig. 5), which prevents the dust and dirt from the cutting head from entering the space occupied by the bearing ring 25.

The cam cylinder 15 is provided with a gear-wheel 36, having internally projecting teeth 37, which are engaged by a pinion 39 for rotating the cam cylinder 15. The pinion 39 is rotated by a motor 40, through gear wheels 41 and 42. The latter is secured upon the shaft 43 having a worm 44 thereon, which worm drives the worm-wheel 45 upon the shaft 46 on which the pinion 39 is secured.

The shaft 46 carrying the pinion 39 is rotatably mounted in the bearings 47 of the housing 48 for the worm-wheel 45. The housing 48 is rigidly secured upon a flange or bracket 49, projecting from the bearing flange 20.

45 The cam proper, having the cam face 16, forms part of the cam cylinder 15 and is formed by the enlarged members 50 and 51 connected by radial ribs 52, more clearly shown in Figs. 4 and 5. Said ribs 52 extend longitudinally upon the cylindrical surface of the cam cylinder and thus strengthen the annular rib 32, which bears against the bearing ring rollers 27 and takes the end thrust of the cam.

55 The cam face 16, formed by the members 50 and 51, is of spiral formation, and has a low place 17, as shown in Fig. 1. Said low place in the cam is provided for the purpose of forming an open space between the face 60 of the cam and the structure, for the insertion of the bricks, as the building of the structure progresses. Between the members 50 and 51 of the cam is a space forming a continuous groove 54 throughout the face of 65 the cam. Said groove 54 is provided to re-

ceive the rollers 56 of the anti-friction carriages 18 and forms a guide for the carriages.

The carriages 18 are positioned between the face 16 of the cam and the structure. Said carriages 18 do not revolve with the cam cylinder 15. The carriages 18 are provided with wheels 58 and 59 against which the face 16 of the cam presses. Said wheels 58 and 59 are loosely mounted upon a shaft 75 60 secured in the body portion 61 of the carriage 18.

The carriages 18 each consist of the body portion 61, in which the said shaft 60 is secured having the wheels 58 and 59 positioned on each side of the body portion. One of said wheels 59 rides upon the inner member 50 and the other wheel 58 rides upon the outer member 51 of the cam face 16.

The rollers 56 on the carriages 18 travel 85 freely in the groove 54 formed in the face of the cam. Each roller 56 turns loosely upon a bushing 62, secured by a bolt 63 to the body portion 61 of the carriage. The rollers 56 form pivot points upon which the carriages rock and said rollers guide the carriages in relation to the cam face and hold the axis of each carriage a uniform distance from the axis of rotation of the cam cylinder.

95 The carriages 18 are held together by ball and socket joints and thus form a continuous chain or caterpillar, which conforms with the face of the cam.

Each carriage 18 is constructed in the general form of a bell crank lever, as shown in Figs. 7 and 9, one arm 65 of which carries the wheels 58 and 59, which bear against the cam face 16 and the roller 56 which travels in the groove 54 of the cam face and 105 also the socket 68 forming part of the ball joint with the next carriage. All the said bearing points of the carriage are in approximately the same plane upon one of the arms of the bell-crank-lever. The other arm 67 110 of the bell-crank-lever extends at right angles to the axis of the roller 56 on the arm 65 and said arm 67 carries the ball 69 which is mounted in the socket 68 of the next carriage and said arm 67 also carries 115 the presser plate 70 which rests against the brick structure.

The ball 69 formed upon the end of the arm 67 is retained in the socket 68, formed in the body portion 61 by the presser plate 120 70, which overlaps a portion of the ball 69. The presser plate 70 has a recess 71 formed therein conforming with the surface of the ball and is secured to the face of the body portion of the carriage by bolts 72. Said 125 plate 70 has a lug 73 formed upon the under side thereof which fits into the larger recess 74 formed in the body portion 61. The lug 73 forms an additional thickness in the plate 70 for the formation of the 130

spherical recess 71 conforming with the surface of the ball 69.

The body portion 61 is provided with lugs 76 and 77 for retaining the ball 69 in its socket 68, which latter is formed partly in the said lugs which are recessed to conform with the surface of the ball. Said lugs are spaced apart and provided with flaring surfaces 78 and 79 for the free sidewise movement of the arm 67 carrying the ball, and the open space between the lugs extending from the bottom of the groove 68, formed in the body portion, to the edge of the overlapping presser plate 70 permits of free movement in the opposite direction of the arm 67. It will be seen that the universal joints provided between the carriages permit of sufficient flexibility in the caterpillar to allow the carriages to follow the contour of the face of the cam 16 including the low portion 17, shown in Fig. 1.

The cam cylinder 15 is provided with an extension, in the form of an inner cylindrical shell 80 secured to the cam cylinder 15. Said shell 80 projects beyond the wheels 59 of the carriages 18. Upon the outer surface of said shell 80 is secured an annular guide-bar or track 81 which follows the contour of the cam face 16. The wheels 59 of the carriages ride against said track 81 throughout the low portion 17 of the cam and hold the carriages adjacent to the cam face 16 and said track 81 thus draws the carriages away from the bricks or blocks forming the structure, thus providing a free space for the insertion of a brick into the structure upon each revolution of the cam cylinder as the low portion of the cam comes opposite to the space in the structure into which the new brick is to be inserted.

A cylindrical shield 85 is provided within the cylindrical structure 13 formed by the bricks. The shield 85 is advanced by hand, or automatically, as the work progresses and it retains the cement or plaster in which the bricks are laid and prevents the same from falling from the upper portion of the structure.

The operation of my invention is as follows: An excavation is made in the ground of sufficient dimensions to receive the machine at the level on which the sewer is to be built; a starting form having a spiral face is anchored in a fixed position adjacent to the end of the casing 1 so that the spiral face 16 of the cam 15, as it rotates, will press the antifriction carriages 18 against the face of the starting form, and the machine will thus be advanced by the action of the cam against the starting form; as the cam rotates within the casing and as the low place in the cam comes opposite to the proper place in the starting form in which the first brick or block is to be inserted, the brick is put in place and the cam as it further

rotates presses the antifriction carriage against the brick, forcing the latter into place and further advancing the machine. A new brick is inserted on each revolution of the cam, and the cylindrical structure 70 is thus formed by successively placing bricks into structure when the low place in the cam withdraws the carriages from the face of the structure a sufficient distance to allow a brick to be inserted in its proper place to form the cylindrical structure having a spiral end face. The cutter head is rotated by a separate motor 9, and makes a cylindrical excavation into which the casing 1 is advanced by the action of the spiral cam pressing the carriages against the spiral face of the cylindrical brick structure. The cam is rotated, independently of the cutter head, by the motor 40 through the chain of gear wheels engaging the ring gear 36 secured to the cam cylinder 15. The bearing flange 20, secured in the casing 1, holds the cam against longitudinal displacement in relation to the casing.

Between the face 16 of the cam and the face of the brick structure are the anti-friction carriages 18, having wheels against which the face of the cam presses. Each carriage has a presser plate 70 which is forced against the face of the bricks by the rotary movement of the cam. The carriages are pivotally secured together and form a continuous chain or caterpillar.

The cam is provided with a low place in its face to form a space for the insertion of the bricks or blocks. The carriages follow the contour of the face of the cam and are drawn away from the face of the brick structure, by the annular guide bar 81 on the cam, thus an open space is formed for the insertion of a new brick into the structure between the carriages and the structure, at the low place of the cam at each revolution of the latter.

Having thus described my invention, I claim and desire to secure by Letters Patent:

1. A machine for building tunnels and the like, having in combination, a casing, an annular bearing flange secured within the casing, said bearing flange having a cylindrical track thereon, an annular bearing surface upon the bearing flange, a bearing ring, rollers loosely mounted upon the bearing ring adapted to travel upon the said cylindrical track and upon the said annular bearing surface of the bearing flange, and a cam cylinder rotatably mounted upon the said rollers of the bearing ring.

2. A machine for building tunnels and the like, having in combination, a cylindrical casing, a bearing flange secured within the casing, a bearing ring, a set of rollers mounted upon axes in the bearing ring extending parallel with the axis of rotation

- of the bearing ring, a set of rollers mounted upon axes in the bearing extending radially from the center of the bearing ring, a cam cylinder having a cylindrical facing surface 5 adapted to travel upon one set of said rollers of the bearing ring, and an annular rib upon the cam cylinder adapted to bear against the other set of rollers of the bearing ring.
- 10 3. A machine for building tunnels and the like, having in combination, a cylindrical casing, a bearing flange secured to the casing, a bearing ring, rollers mounted upon the bearing ring adapted to travel 15 upon the bearing flange, a cam cylinder mounted upon the rollers of the bearing ring, and a detachable flange plate secured to the cam cylinder adapted to overlap the bearing flange and hold the cam cylinder 20 adjacent to the bearing ring.
4. A machine for building tunnels and the like, having in combination, a cylindrical casing, a bearing flange of cylindrical formation secured upon the inner surface of the 25 casing, said bearing flange having an internal cylindrical bearing surface thereon, said bearing flange having an inwardly projecting annular flange having a bearing facing surface thereon, a cam cylinder rotatably mounted within the casing, and anti-friction members positioned between the cam cylinder and the said bearing surfaces 30 of the bearing flange.
5. A machine for building tunnels and the like, having in combination, a cylindrical casing, a bearing flange of cylindrical formation secured upon the inner surface of the casing, a cam cylinder rotatably mounted upon the bearing flange, and a dust ring positioned between the exterior cylindrical 35 surface of the cam cylinder and the cylindrical surface of the bearing flange.
6. A machine for building tunnels and the like, having in combination, a cylindrical casing, a bearing flange of cylindrical formation secured upon the inner surface of the casing, a cam cylinder rotatably mounted upon the bearing flange, a gear ring secured within the cam cylinder, said gear 45 ring having internally projecting teeth formed thereon, a pinion meshing with the gear ring, a shaft upon which said pinion is mounted, a bearing in which said shaft is rotatably mounted, a bracket formed upon the 50 said bearing flange to which the bearing carrying said shaft is secured, and means for rotating the said shaft.
7. A machine for building tunnels and the like, having in combination, a cylindrical casing, a bearing flange of cylindrical formation secured upon the inner surface of the casing, a cam cylinder rotatably mounted upon the bearing flange, a ring gear secured to the cam cylinder, a pinion meshing 55
- with the ring gear, a shaft carrying the pinion, a bearing secured in a fixed position in which said shaft is rotatably mounted, a worm-wheel upon said shaft, a worm for driving the worm-wheel mounted upon said bearing, and means for rotating the 60 said worm.
8. A machine for building tunnels and the like, having in combination a casing, a bearing flange secured within the casing, a cam cylinder rotatably mounted upon the 65 bearing flange, an annular rib formed upon the outside of the cam cylinder, a facing surface formed upon the said rib, anti-friction members positioned between said rib and the bearing flange, a cam member formed upon the cam cylinder, and radial ribs upon the cam cylinder extending between the said annular rib of the cam cylinder and the cam member of the cam cylinder.
9. A machine for building tunnels and the like, having in combination, a casing, a bearing flange secured within the casing, a cam cylinder rotatably mounted upon the bearing flange, an annular rib formed upon the 75 outside of the cam cylinder, a facing surface formed upon the said rib, anti-friction members positioned between said rib and the bearing flange, enlarged cam members formed upon the cam cylinder, ribs upon the cam cylinder carrying the outer one of said cam members, said cam members being spaced apart to form a concentric annular groove between them, anti-friction carriages positioned adjacent to the cam 80 members, and a member upon said carriages adapted to occupy the said groove formed between the cam members for guiding the carriages.
10. A machine for building tunnels and the like, having in combination, a casing, a cam cylinder rotatably mounted within the casing, a cam face formed upon one end of the cam cylinder, anti-friction carriages, a wheel upon each carriage adapted to ride upon the cam face, a cylindrical extension upon the cam cylinder extending beyond the wheel of the carriage, and a track mounted upon the said cylindrical extension against which the wheel of the carriage 90 may ride when not in contact with the face of the cam.
11. A machine for building tunnels and the like, having in combination, a casing, a cam cylinder rotatably mounted within the 95 casing, a cam face formed upon one end of the cam cylinder, said cam face having an annular groove formed in the face thereof, anti-friction carriages, a roller upon each carriage adapted to occupy the said groove formed in the cam face, a wheel upon the carriage adapted to ride upon the face of the cam, a track carried by the cam cylinder.

inder for engaging the wheel of the carriage and holding the roller of the carriage in the said groove in the cam face.

12. A machine for building tunnels and the like, having in combination, a casing, a cam cylinder rotatably mounted within the casing, a cam face formed upon one end of the cam cylinder, anti-friction carriages, a wheel upon each carriage adapted to ride upon the face of the cam and means for connecting the carriages together to form a continuous flexible member extending throughout the face of the cam.

13. A machine for building tunnels and the like, having in combination, a casing, a cam cylinder rotatably mounted within the casing, a cam face formed upon one end of the cam cylinder, anti-friction carriages, a wheel upon each carriage adapted to ride upon the face of the cam, and a ball and socket connection between each carriage for forming a continuous flexible member extending throughout the face of the cam.

14. A machine for building tunnels and the like, having in combination, a casing, a cam cylinder rotatably mounted within the casing, a cam face formed upon one end of the cam cylinder, anti-friction carriages, a wheel upon each carriage adapted to ride upon the face of the cam, a body portion forming part of the carriage and carrying said wheel, said body portion having a recess formed therein, an arm on the body portion, a ball formed upon the end of the arm adapted to enter the recess formed in the next adjoining carriage, and a plate secured upon the body portion for securing the ball in the said recess formed in the body portion of the carriage.

15. A machine for building tunnels and the like, having in combination, a casing, a cam cylinder rotatably mounted within the casing, a cam face formed upon one end of the cam cylinder, anti-friction carriages, a wheel upon each carriage adapted to ride upon the face of the cam, a body portion forming part of each carriage and carrying said wheel, said body portion having a recess formed therein, an arm on the body portion, a ball formed upon the end of the arm adapted to enter the recess formed upon in the next adjoining carriage, lugs formed upon the body portion projecting at either side of the arm carrying the ball, and a presser plate secured upon the body portion adapted to retain the ball in the recess formed in the body portion.

16. A machine for building tunnels and the like, having in combination, a casing, a cam cylinder rotatably mounted within the casing, a cam face formed upon one end of the cam cylinder, anti-friction carriages, a wheel upon each carriage adapted to ride upon the face of the cam, a body portion forming part of each carriage and carrying said wheel, a presser plate detachably secured to the body portion, a lug formed upon the under side of the presser plate, said body portion and the said presser plate having a spherical recess formed therein extending partly into the lug of the presser plate, an arm upon the body portion, and a ball formed upon the arm adapted to be retained in the spherical recess formed in the next adjoining carriage by the said detachable presser plate.

17. A machine for building tunnels and the like, having in combination, a casing, a cam cylinder rotatably mounted within the casing, a cam face formed upon one end of the cam cylinder, anti-friction carriages each comprising a body portion, a shaft extending through the body portion, a wheel mounted upon each end of the shaft at opposite sides of the body portion, said wheels adapted to ride upon the face of the cam, an arm extending from each body portion to the next adjacent carriage, means for pivotally connecting the arm with the next adjacent carriage, and a presser plate mounted upon each body portion.

18. A machine for building tunnels and the like, having in combination, a casing, a cam cylinder rotatably mounted within the casing, a cam face formed upon one end of the cam cylinder, said cam face having an annular groove formed in the face thereof, anti-friction carriages each comprising a body portion in the form of a bell-crank, a roller on one arm of the bell-crank adapted to occupy the said groove formed in the face of the cam, a ball formed upon the end of the opposite arm of the bell-crank, said body portion having a spherical recess formed therein adapted to receive the ball of the arm of the next adjacent carriage, wheels mounted upon either side of the body portion adapted to ride upon the cam face, and a presser plate upon the body portion of the carriages.

In testimony whereof I affix my signature.

MILTON ROY SHEEN.
